PROCESS FOR PRODUCING ALKYL ALUMINUM COMPOUNDS

Marcelian F. Gautreaux and Andrew O. Wikman, Baton Rouge, La., assignors to Ethyl Corporation, New York, N.Y., a corporation of Virginia
No Drawing. Filed Nov. 1, 1966, Ser. No. 591,133
Int. Cl. C07f 5/06

U.S. Cl. 260—448

10 Claims

ABSTRACT OF THE DISCLOSURE

The manufacture of alkyl aluminum compounds involving the reaction of aluminum and hydrogen is catalyzed with a complex, partially alkyl, species of titanium, zirconium, or niobium. A typical catalyst precursor is a titanium, zirconium or niobium alkoxide; particularly a lower alkoxide, such as titanium tetraisopropoxide.

This invention relates to the preparation of alkyl compounds of aluminum and in particular to the preparation of such compounds by the direct process from hydrogen, aluminum and ethylene employing catalytic materials.

The direct reaction of aluminum with hydrogen and olefin to produce trialkylaluminum compounds is disclosed by Horace E. Redman in U.S. Patent 2,787,626 issued Apr. 2, 1957. As a result of this teaching and others related to it the manufacture of trialkylaluminum compounds has become a large-scale commercial operation. In such reaction, the "activation" of aluminum appears to be an important consideration. Numerous variations relating to the "activation" of aluminum in this type reaction as well as in others have been set forth, typical of these being activation with sodium materials in the United States patents of Herbert B. Fernald, 3,077,490 and 3,100,786, issued Feb. 12, 1963 and Aug. 13, 1963, respectively. Other patents in this area include the U.S. patents to Elmer H. Dobratz, 2,892,738; 2,908,562 and 3,026,345 issued June 30, 1959, Oct. 13, 1959 and Mar. 20, 1962, respectively.

Another activation arrangement for aluminum is disclosed by Frederick J. Radd and Warren W. Woods in U.S. Patent 3,104,252 which issued Sept. 17, 1963, in which the aluminum reactant is in the form of an alloy containing an "added reaction promoting amount" of one or more of several catalytic elements, titanium, zirconium, hafnium, vanadium, niobium, scandium, and uranium. This activation involves certain metals which are said to form peritectic binary systems with aluminum and mentions that, of 51 metallic elements tested in aluminum alloys for the purposes of the invention, only the seven noted above have been found to work as activators. Aside from general discussions along the line indicated, the patent does not develop much theory as to mechanism however it is believed that the titanium alters the crystal structure of aluminum and makes it more capable of reaction with hydrogen.

Another line of patents relating to the "activation" of aluminum involve halogens as shown in the patent to Ziegler which issued in the Republic of South Africa as No. 263/55 and the patent to Dow which issued in Belgium as 548,652.

Another prior art patent in this general area, U.S. 2,271,956 to Ruthruff, indicates that the reaction of olefin, aluminum, and hydrogen in the presence of an aluminum halide yields dialkylaluminum halide and monoalkylaluminum dihalides. Associating this teaching with the teachings of Ziegler's South African patent and noting the discussion as to activation of aluminum in the various teachings, it is with considerable interest that one notes that

2

the elements which are considered to be inhibitors or poisons for the reaction in U.S. Patent 3,104,252 are considered to be activators of aluminum for the reaction of 2,271,956.

Together the foregoing patents deal with the so-called activation of aluminum by the elements and inorganic and organic compounds of the alkali metals and alkaline earth metal classes (I-A and II-A), as well as heels of organoaluminum compounds. Additionally elements of 5 the scandium and titanium classes (III-B and IV-B) are mentioned as activators as are the halogens (VIII-A). Certain classes of transition metals are discussed as both activators of aluminum and reaction inhibitors. Other materials, such as silicon are also discussed as both inhibitors and activators. As an example for silicon U.S. 15 3,104,252 discusses one side and French Patent 1,409,564 discusses the other. To this last group as far as inhibitors are concerned perhaps can be added oxygen and oxygen containing materials because of the tendency of oxygen 20 to form an inactive Al_2O_3 film that supposedly is removed in the early described Ziegler ball-mill technique. Also carbon and nitrogen probably tend to suppress the reaction by dilution without solution. (Note that the 25 classes referred to above are those as set forth in the 1955 Periodic Chart of the Fisher Scientific Company.)

All of the foregoing activator materials except the "heel" are contaminants as far as a high purity trialkyl aluminum product is concerned. Of more serious consequences, some of these materials (such as sodium) form 30 active compounds or complexes with aluminum and some of them such as titanium form highly active catalysts for certain reactions such as ethylene polymerization that are undesired in certain instances where the product trialkylaluminum compounds are used, as for example as a basic 35 building block for controlled chain growth with ethylene. Thus, aside from the expense involved, one seeks to hold to a minimum the amount of additive used. In many instances this is a difficult proposition because it is not generally possible to determine much in advance how a 40 particular combination of reactant lots will behave. Thus one must usually specify an operating procedure or materials which will react under the most adverse conditions. Reaction will be obtained but uniformity of product is still missing. Particularly is this true with the titanium-alloy of U.S. Patent 3,104,252 because alloys are notorious for variable properties and any additive thereto must be inserted far in advance of the reaction and cannot be 45 conveniently changed after the formulation of the alloy. Thus it is not unusual that titanium quantities vastly 50 greater than the 100–500 parts per million quantity seemingly adequate in accordance with U.S. Patent 3,104,252 are usually used by proponents of the alloy system.

In view of the state of the art with regard to the "activation" of aluminum in the preparation of alkyl aluminum compounds, it is surprising that an entirely new technique for enhancing the production of alkyl aluminum compounds has been discovered which provides substantial improvement with a comparative simplicity of the overall process. The present technique may 55 be employed to advantage as the sole intentional improvement for this type of reaction yet on the other hand it may be combined to advantage with various forms of "activation" previously known intentional or otherwise such as those discussed in the foregoing. The improvement of the present invention preferably uses organo compounds of titanium and related materials as catalysts. These catalysts can be added to the reactants or to the reaction mass itself on an individual-batch or instantaneous-concentration basis which can be manipulated at will so as to maintain a high degree of uniformity 60 in reaction rate with minimum contamination of the product. Catalysts can be added directly or generated 65 70

in situ from precursor materials. The effectiveness of the titanium and related materials used as catalysts here appears to be vastly greater than that of titanium and like materials used in alloys as aluminum activators. The present technique is particularly advantageous in cooperation with the sodium activation and heel techniques discussed in the foregoing, it appearing that these different "activation" techniques plus the catalysis may influence different ones of many sequential reactions involved in the overall process, the actual activation of aluminum possibly being only one of several such sequential reactions, with the catalytic factor influencing the rate controlling reaction.

Likewise the present catalysis teachings can be used in combination with residual titanium class materials in the aluminum in the sense that prior removal of all traces of such from the aluminum is not necessary. In many instances, however, one does not wish to have routinely present a high content of titanium class materials because of carry-over to the trialkyl aluminum product and prefers to pay extra for higher purity aluminum and use the teachings of the present invention which permits variation of amount of organo titanium and related materials even from batch to batch for precise control and greater uniformity of reaction and product.

The constituents of the class identified as titanium and related material include the members of Groups III-B, IV-B and V-B of the Periodic Table (Fisher Scientific Company, 1955). In general, organo titanium and to a lesser extent organo zirconium materials are preferred catalysts on a cost-effectiveness basis. Organo niobium materials are useful but less preferred. Specific compounds particularly desirable are organo materials such as alkoxides having comparatively small numbers of carbon atoms per organo radical because of their desirable physical characteristics particularly as regards stability, availability, boiling point and melting point, and because of their greater percentage of active metal bonds available on a weight basis. Since alkyls of titanium and many related materials are not particularly stable and are not easy to produce and isolate, a preferred form which possesses desired characteristics for the purposes of the present invention includes the alkoxides, particularly those of the lower organo groups such as those having from about 2-6 carbon atoms per organo radical. Uniform materials such as titanium isopropoxide and alkyl-alkoxide combinations of various ratios can be used as well as mixtures involving radicals with up to about 20 carbon atoms per organo radical. Another basis for describing the catalyst which is desirable in some instances is to use compounds in which the carbon chains of the organo radicals correspond to the desired product alkyls, simplifying purification operations. Thus titanium ethoxide (tetraethoxy-titanium) and ethyl triethoxy titanium may be used in preparing triethyl-aluminum. Titanium isopropoxide has excellent catalytic characteristics in connection with the production of the lower alkyl aluminum compounds, such as triethylaluminum and triisobutylaluminum, particularly in the direct reaction of olefin, aluminum and hydrogen combined with sodium activation and the use of a heel from a previous run, the latter activations being used as taught in the prior art. Using such technique it is generally possible to obtain excellent results in the production of triethylaluminum using comparatively small quantities of titanium tetraisopropoxide such as about 0.01 to 5.0 percent by weight of catalyst fed relative to aluminum fed. A more preferred catalyst proportion is from about 0.04 to about 2.0 percent by weight with from about 0.05 to about 1.0 most preferred. These ratios are on the basis of a particular compound (tetraisopropoxy titanium) and therefore depend to some extent upon the particular form and size of alkyl radicals involved. Other materials will normally be used in ratios giving equivalent mols of metal alkoxide fed per gram

atom of aluminum fed. In general, the broad ranges include the workable and desirable ranges which are preferred because they fall between one limit of excessive catalyst for purchase cost and separation expense considerations and the other limit of negligible effectiveness.

To illustrate the magnitude of the improvement readily obtainable when utilizing the teachings of the present invention, comparative data show an increase in reaction rate by a factor of approximately 25 when titanium alkoxide is added to a poorly reactive aluminum system when used on the basis of about 0.8 wt. percent of tetraisopropoxy titanium relative to aluminum in the reactants fed.

The reason for the great effectiveness of the catalysts is not known however certain theories seem plausible. Surprisingly, one cannot achieve results such as those of the present invention by adding titanium powder or titanium hydride to the reaction mass. Even titanium dioxide is not as effective as the present systems. This seemingly eliminates the possibility that elemental titanium or titanium metal per se is a catalyst or is convertible into a catalytic species by reactions in the aluminum-hydrogen-olefin system. The fact that titanium hydride does not show results seemingly rules out its participation as a catalyst in corresponding metal hydride reactions with olefin which parallels the AlH_3 type of reaction to form titanium alkyls. Literature information also appears to bear this out by emphasizing the unstable nature of titanium alkyls leading one to suspect that they might not be formed in the first place. Titanium dioxide seems to be rather insoluble.

It is believed that a fundamental or rate limiting step in the reaction of aluminum, hydrogen and olefin is a reaction of aluminum and hydrogen to produce some form of aluminum hydride species according to a reaction such as:

This involves a five body collision of materials in different phases (solid phase and liquid phase) which has a low probability.

Where the principles of the present invention are used, it is believed that a far simpler tri-molecular type of reaction occurs (as shown for titanium materials):

In this instance the collisions of reactants are much simpler and the hydrogen and titanium alkoxide are more closely related to a solution condition so that the reaction can occur. The variable valence of titanium is also believed to be a contributing factor in its change from the n to the $n-1$ state, n usually being 4.

Probably this is a simplification as to the species of titanium material that is the effective catalyst and also in that catalyst regeneration is not shown however, once the possibility of such is established, it is quite evident that here we can have a catalytic system in comparison to a mere aluminum activation system which seeks to make the aluminum more susceptible to reaction in the 5-body collision type of reaction.

Various possibilities in reaction such as (B) above can be considered particularly as regards the effective catalytic species and the various possible exchanges in which it can become involved.

In the first place it is believed likely that the effective catalytic species is a complex partially alkyl species such as:

where

70 M is titanium, zirconium or niobium, or mixtures thereof.

R is hydrocarbon alkyl, aryl, alkaryl, arakyl, cycloalkyl and the like and may contain compatible substituents.

R is preferably lower alkyl up to about 6 carbon atoms.

75 x+y is a valence factor which is 4 where M is titanium

and zirconium and 3 where M is niobium; x can be zero or positive, but not negative.

Z is $-\text{OR}'$, where R' is as R above plus Ti and Al , which are moieties of titanium and aluminum respectively, a moiety representing merely a partial molecular structure where is shown only one bond of a titanium or aluminum atom involved at that point. Such a configuration normally is related to a bridging or association of two M atoms via the "O" linkage. R and R' can be similar or different and where y is greater than 1, the Z 's can be similar or different.

The foregoing effective catalysts can be supplied to the system in such form or can be generated in situ from precursor materials, particularly M alkoxides, such as lower titanium alkoxides; for example, tetraethoxy titanium, tetraisopropoxy titanium, tetrabutoxy titanium and the like. A precursor material that is frequently particularly desirable because of the ease and low cost of producing it as above and comparative ease of handling is tetraisopropoxy titanium.

Where such a precursor material is supplied to an AlR_3 reaction system such as a triethylaluminum system or a triisobutylaluminum system, a first probable reaction (shown for typical tetraalkoxy titanium) is the in-situ generation of the effective catalyst R_xTiZ_y according to the reaction:

The involvement of R_xTiZ_y in the reaction with aluminum and hydrogen may come about through an R exchange or a Z exchange or both. The R exchange is simpler and is discussed first with the aid of the following reaction sequence:

In Equation 1 the catalyst R_xTiZ_y is "reduced" to a lower valence state which in turn goes to a further lower valence state in a second step of Equation 2. In each of Equations 1 and 2 aluminum alkyl dihydride is formed as a short lived intermediate which is soluble and hence readily reactive with soluble olefin in a bi-molecular fashion according to Equation 3 to produce R_3Al without further necessity for involvement of the catalyst. The catalyst is regenerated in Equation 4 with hydrogen and olefin, however, a similar regeneration may occur in the presence of hydrogen and a "heel" of AlR_3 through a splitting-off of alkyl residues.

A similar series of reactions occurs with the Z exchange however there is greater complication at this point because of a greater number of alternate reaction possibilities due in part to concurrent R and Z exchanges.

From the above it is observed that sequential reactions are shown in which the five-body collision requirement of the aluminum-hydrogen reaction is avoided and solubilities are comparatively favorable. It is believed that to avoid making erroneous generalizations it is desirable to point out that certain titanium salts particularly TiCl_4 are known to have desirable effect in olefin polymerization and in the displacement of hydrocarbon residues from aluminum through a process of splitting off the original hydrocarbon residues as olefins and the attachment of the new olefins in their place as different hy-

drocarbon residues. Both of these known processes can be placed in the same category by regarding them as the addition of an olefin to an aluminum-hydrogen bond (displacement) or to an aluminum-hydrocarbon bond (polymerization). These are of the nature of reactions (3) and (3') above. The present catalyst systems are believed to operate with regard to the different reactions of (1), (1'), (2), (2'), (2''), (2'') above, which are not involved in polymerization and displacement.

- 10 In the following examples, two grades of aluminum were employed for comparative purposes. The first grade (for Examples 1 and 2) was of comparatively high purity in the range of 99.7-99.9 percent aluminum. Other impurities were quite small and a sample was selected 15 as typical material of low titanium and silicon content (less than 50 parts per million) so as to avoid any alloy activation thereby. The reaction proceeded well in non-catalyzed Example 1 but significantly better when catalyst was added in Example 2.
- 20 For Example 3, etc., a lower grade of aluminum was chosen as a typical inexpensive production grade which had given poor results in previous experimentation. This material was fairly low in iron contamination but without any outstanding content of any particular contaminant, 25 particularly titanium and silicon.

EXAMPLE 1

A mixture of 73 g. of triethylaluminum, 35 g. of finely-divided aluminum powder, and 0.3 g. of sodium was 30 heated to 140° C. in a 250-ml. turbine-agitated Magne-Drive autoclave under 1000 p.s.i.g. hydrogen pressure. Hydrogen to maintain the pressure constant at 1000 p.s.i.g. was fed continuously to the autoclave from a 250-ml. feed reservoir maintained at a higher pressure. The pressure drop in the feed reservoir was plotted as a function of time and the maximum slope of this line was taken as a measure of the relative reaction rate, which varies with the reactivity of the aluminum powder employed. A 35 slope equivalent to 200 p.s.i.g. pressure drop in 35 minutes is arbitrarily assigned a relative reactivity of 1.00. In this example, the relative reactivity was found to be 0.79. This method of experimentation was selected because it is representative of the rate determining aluminum plus hydrogen reaction and minimizes indeterminate variables 40 such as hydrogenation of olefin. Results are comparable 45 in general when olefins are used for the complete sequence.

EXAMPLE 2

50 Example 1 was repeated, using the same grade of aluminum powder, with the addition of 0.25 g. of titanium isopropoxide. The relative reactivity was 2.23.

EXAMPLE 3

55 Example 1 was repeated, using a different grade of aluminum powder. The relative reactivity was 0.20. This same grade of aluminum powder was used in Examples 4-10.

EXAMPLE 4

60 Example 3 was repeated, with the addition of 0.25 g. of titanium isopropoxide. The relative reactivity was 5.4.

EXAMPLE 5

65 Example 3 was repeated, with the addition of 0.05 g. of titanium isopropoxide. The relative reactivity was 2.2.

EXAMPLE 6

70 Example 3 was repeated, with addition of 0.125 g. of zirconium isopropoxide. The relative reactivity was 3.7.

EXAMPLE 7

Example 3 was repeated, with the addition of 0.036 g. of zirconium hydride. The reaction proceeded too slowly to measure a relative reactivity.

EXAMPLE 8

Example 3 was repeated, with the addition of 0.072 g. of titanium hydride. The reaction proceeded too slowly to measure a relative reactivity.

EXAMPLE 9

Example 3 was repeated, with the addition of 0.02 g. of finely-divided titanium powder. The reaction proceeded too slowly to measure a relative reactivity.

EXAMPLE 10

Example 3 was repeated, with the addition of 0.12 g. of titanium dioxide. The reaction proceeded too slowly to measure a relative reactivity. The unsuccessful Examples 9-12 illustrate that it is not merely the choice of the metal component of the catalyst which is important and points out the necessity for selecting the catalyst in accordance with the teachings of this invention.

EXAMPLE 11

Example 1 is repeated using various grades of aluminum with various amounts of impurities elements present, with various olefins and with various R_xMZ_y compounds as defined herein. Similar results are obtained showing improved rate with catalyst presence. Particularly significant are experiments with the alkoxides of titanium and with catalyst concentration of from 0.01 to 5 percent by weight of catalyst based on the amount of aluminum powder.

It is seen from the foregoing that excellent results are obtained where the catalyst species is obtained with the actual total titanium class materials in the feed being quite low, e.g. in Example 5, the amount of titanium relative to aluminum is about 0.14 percent by weight and numerous experiments show that 0.1 percent and 0.05 percent are generally quite satisfactory. These correspond to about 230, 160 and 80 parts per million of titanium. Holding the titanium as low as possible is highly important in maintaining low titanium contamination of product aluminum alkyls because of the adverse catalytic effect of titanium and its compounds in many subsequent reactions of the aluminum alkyls.

What is claimed is:

1. In a process for producing alkyl aluminum compounds from reactants comprising aluminum and hydrogen and olefin or alkyl aluminum or both the improvement which comprises:

catalyzing the reaction with from about 0.01 percent to about 5 percent by weight of a compound R_xMZ_y where,

M is selected from the group consisting of titanium, zirconium and niobium and mixtures thereof, R is hydrocarbon,

$x+y$ is a valence factor for M , wherein x can be zero or positive,

45
50
55

Z is $-OR'$ wherein R' is hydrocarbon similar to R or different and where Z is plural, they can be similar or different.

2. The process of claim 1 wherein the reactants are aluminum, hydrogen and olefin.

3. The process of claim 1 wherein the reactants are aluminum, hydrogen and aluminum alkyl.

4. The process of claim 1 wherein the reactants are aluminum, hydrogen, olefin and aluminum alkyl.

5. The process of claim 1 wherein the compound is R_xTiZ_y where,

R is hydrocarbon,

$x+y$ is a valence factor for Ti , wherein x can be zero or positive,

Z is $-OR'$ wherein R' is hydrocarbon, similar to R or different, and where Z is plural, they can be similar or different.

6. The process of claim 1 wherein the compound is fed as $M(OR')_y$ where,

M is selected from the group consisting of titanium, zirconium and niobium, and mixtures thereof,

y is a valence factor for M ,

R is similar or different hydrocarbon.

7. The process of claim 1 wherein the compound is fed as $Ti(OR')_4$ where,

R' is similar or different hydrocarbon.

8. The process of claim 1 wherein the catalyst is generated in situ from a compound of the type $M(OR')_y$ added to the reaction system, where

M is selected from the group consisting of titanium, zirconium and niobium, and mixtures thereof,

y is a valence factor for M ,

R' is similar or different hydrocarbon.

9. The process of claim 1 wherein the catalyst used is a lower tetraalkoxy titanium compound supplied in the proportion of from about 0.025 to about 2.0 weight percent based on the aluminum.

10. The process of claim 1 wherein the catalyst used is tetraisopropoxy titanium supplied in the proportion of from about 0.05 to about 0.5 weight percent based on the aluminum.
